United States Patent Office.

J. E. JINKINS, OF MILTON, FLORIDA.

Letters Patent No. 69,999, dated October 22, 1867.

IMPROVEMENT IN PLOUGHS.

The Schedule referred to in these Letters Patent and making part of the same.

TO ALL WHOM IT MAY CONCERN:

Be it known that I, J. E. JINKINS, of Milton, in the county of Santa Rosa, and State of Florida, have invented a new and improved Plough, and that the following description, taken in connection with the accompanying drawings hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and useful improvement in the construction of ploughs, whereby the same may with the greatest facility be made to penetrate the earth at a greater or less depth, and the plough also adapted for scraping or surface culture when required. In the accompanying sheet of drawings—

Figure 1 is a side view of my invention.

Figure 2, a section of the same taken in the line $x-x$, fig. 1.

Figure 3, a front view of the same.

Similar letters of reference indicate like parts.

A represents a frame, which may be of cast or wrought iron, and has its front bar a bevelled, so as to form an oblique surface transversely with the bar, as shown clearly in fig. 2. This bar a is curved longitudinally, as shown in fig. 1, and said bar has an oblong slot, b , made through it, through which slot a bolt, B , passes, which secures the share C to the bar a . D is a cap, through which the bolt B also passes. This cap is fitted over the share C , the head of the bolt B bearing against its outer surface, and a washer, e , and nut d , being behind the front bar a . It will be seen from this description that the oblong slot b admits of the share C being adjusted higher or lower, according to the depth required for it to penetrate into the earth. To the left-hand side of the bar a there is secured a side cutter, D^X , which is designed to be used as a scraper to scrape away the surface soil adjoining the plants. This side cutter is attached to the bar a by bolts e , which pass through oblong slots f in the cutter, said slots admitting of the cutter being adjusted further forward or backward in an oblique direction, so that the cutter may scrape the earth at a greater or less depth as desired. The frame A is secured to the beam of the plough in the usual or any proper manner, and said frame may have a wing or mould-board attached for turning over the earth when required.

Having thus described my invention, I claim as new, and desire to secure by Letters Patent—

1. The adjustable share C applied to the front bar a of the frame A of the plough, substantially as and for the purpose specified.

2. The adjustable side cutter or scraper D^X , in combination with the adjustable share C and frame A , substantially as and for the purpose set forth.

3. The sliding cap D , in combination with the share C and frame A , all arranged to operate in the manner substantially as and for the purpose specified.

J. E. JINKINS.
